COMBINED SWIMMING POOL PUMP AND STRAINER

Harry M. Clinton, Northridge, Calif., assignor to Swim-rite Manufacturing Co., Inc., Van Nuys, Calif.

Filed Aug. 3, 1970, Ser. No. 24,266

Term of patent 14 years

Int. Cl. D23—01; D15—02

U.S. Cl. D23—4

FIG. 1 is a front perspective view of a combined swimming pool pump and strainer embodying my new design;

FIG. 2 is a side elevational view thereof taken from the rear side of FIG. 1;

FIG. 3 is a side elevational view taken from the right side of FIG. 2; and

FIG. 4 is a bottom plan view thereof.

I claim:

The ornamental design for a combined swimming pool pump and strainer, as shown.
